(21) Appl. No.: **29/175,127**

The ornamental design for an interior illuminated lamp in the shape of a tractor, as shown and described.

(22) Filed: **Jan. 31, 2003**

DESCRIPTION

(51) LOC (7) Cl. **26-03**

FIG. 1 is a view in perspective of the present invention;

(52) U.S. Cl. **D26/97**

FIG. 2 is a left side view of the present invention;

(58) Field of Search D26/94, 97, 104;

362/410-414, 806; D21/431, 537; D15/10,

15, 22-26; 446/433-435, 427, 465, 470;

D11/133, 163; 180/89.12, 900

FIG. 4 is a front view of the present invention;

FIG. 5 is a back view of the present invention;

FIG. 6 is a top view of the present invention; and,

FIG. 7 is a bottom view of the present invention.
